UNITED STATES PATENT OFFICE.

GEORGE E. STEPHENSON, OF CHICAGO, ILLINOIS.

SPOTLIGHT COLOR SCREEN.

Application filed December 9, 1921. Serial No. 521,165.

To all whom it may concern:

Be it known that I, GEORGE E. STEPHENSON, a citizen of the United States, residing at Chicago, in the county of Cook and State of Illinois, have invented certain new and useful Improvements in Spotlight Color Screens, of which the following is a description.

My invention relates to improvements in spot lights and color screens therefor, and more particularly to a spot light provided with a revolving color screen which may be controlled, as desired, and means for adjusting the same as desired, the drive means for rotating said screen being uninterruptedly operated even while adjustments are being made.

Another object of my invention is to provide a single drive means suitable for a battery of any number of spot lights and color screens, and wherein any of said screens may be individually adjusted without interrupting said drive.

The invention has among its other objects the production of a device of the kind described which is simple, convenient, compact, durable, reliable, efficient and satisfactory for use wherever found applicable.

To this end my invention consists in the novel construction, arrangement and combination of parts herein shown and described, and more particularly pointed out in the claims.

In the drawings, wherein like reference characters indicate like or corresponding parts.

Fig. 1 is a top plan view of my device;

Fig. 2 is an elevation thereof taken in the rear of Fig. 1;

Fig. 3 is a sectional view taken substantially on the line 3—3 of Fig. 2;

Fig. 4 is a sectional view taken substantially on the line 4—4 of Fig. 1;

Fig. 5 is a sectional view taken substantially on the line 5—5 of Fig. 4;

Fig. 6 is a sectional view taken substantially on the line 6—6 of Fig. 4;

Fig. 7 is a sectional view taken substantially on the line 7—7 of Fig. 4;

Fig. 8 is a sectional view taken substantially on the line 8—8 of Fig. 2, and

Fig. 9 is a sectional view taken substantially on the line 9—9 of Fig. 8.

Referring to the drawings, wherein I have illustrated the preferred embodiment of my invention and several associated devices,

there is shown a battery of spot lights arranged one adjacent the other and comprising any number. Each spot light has therein a lamp 1 of any suitable size or shape and mounted on a suitable frame or base 2, the frame shown being in the form of a housing or casing of suitable size, shape and material. A lens 3 is mounted in one of the side walls of said lamp housing so that the rays of light from said lamp may be directed as desired. The energy for the lamp 1 is conducted thereto by a lead wire 4 from a suitable source of energy. Preferably secured to the opposite sides of the housing 2 and projecting in opposite directions are bosses or lugs 5 and 6 for supporting said housing, as will be more clearly hereinafter described.

A bracket, preferably in the shape of a J, in that it has a pair of parallel legs 7 and 8, one shorter than the other, and with a transverse connecting portion at one end, is provided to adjustably carry the housing 2. The bracket 7—8 comprises two sections which may be telescopically connected to each other at their transverse portions 7', 8', and detachably held together by a set screw 9 or the like. The free end of the shorter leg 7 is provided with a cap 10, adapted to frictionally engage the ends of the lug 5, as shown in Figs. 8 and 9, so that the housing 2 may be adjustably pivoted about the axis of the lug, and a setscrew 11 is arranged to engage both the lug and cap to adjustably hold said housing in the desired position. The other lug 6 acts merely as a centering pin and engages a bearing 6' on a sleeve 12 extending transversely of the longer leg 8 of the bracket (Fig. 7), and preferably carried by or part of a junction box 12' arranged on said leg. Whenever it is desired to remove the lamp casing, the leg 7 of the bracket frame carrying the casing is detached from the longer leg of the bracket, as will be apparent from the construction shown in Figs. 2 and 3, simply by loosening the setscrew 9 and moving the leg 7 away from the leg 8.

The brackets may be supported in any desired manner, depending, as shown, or projecting upwardly, as desired, from a wall, floor or ceiling, by any suitable means. In the present instance there is shown a hollow tube 13, with junction boxes 14 at intervals thereon, and the longer legs 8 of the brackets are adapted to be pivotally connected to

said junction boxes and releasably maintained in pivotal adjustment therewith by set screws 14, or the like. Thus the junction boxes not only serve as junction boxes, but as couplings besides.

It will be noted that the tube 13, together with the junction boxes or couplings and the brackets 7-8 form a conduit through which the wires 4 may be drawn, leading to the lamps 1. At the ends of the tube 13 are transverse tubes 15, for supporting the spot lights in any desired manner, for example from overhead, as indicated in dotted lines (Fig. 2), or for supporting them on the floor, as shown in full lines.

A color screen 16 is arranged to encircle each lamp and housing. The screen consists of a pair of coaxially spaced side members or annular rings 17, 18, each preferably of L-shape in cross-section, so as to be of angle-iron formation, one flange extending radially inwardly and the other flange extending axially inwardly of the screen (Figs. 4 and 6). Brace rods 19 are arranged transversely of the parallel side rings at intervals about the peripheries thereof and are connected at their ends to said rings in any suitable manner. Spokes 20 radiate inwardly of one of said side members, as for instance the member 17, and may be integral with said brace rods or rings, if so desired. The inner ends of said spokes are connected to the hub 21, which is revoluble on the sleeve 12, so that the side frames 17 and 18 are carried by the hub 21 and are revoluble about the lamp.

Annularly arranged about the frames 17, 18, is a series of sheets of colored material 22 of isinglass, celluloid or other suitable material. In order that the sheets 22 may be removably held in place, I have arranged arcuate clamping members 23, angular in cross section, adapted to extend along and be superimposed on the angle-formed rings 17, 18, (Fig. 6) to hold the sheets 22 therebetween. Bolts or screws 24 are inserted through the cooperating angle-shaped members 23, and the members 17 and 18 respectively, to detachably clamp the sheets 22 therebetween.

From the foregoing description it is seen that the lamp housing with the lamp therein is pivotally adjustable on an axis coincident with the rotational axis of the screen, and that the combined housing and screen are pivotally adjustable about the axis of the longer leg 8 of the bracket, these two axes of adjustment being mutually perpendicular to each other.

The rotatable screen 16 may be driven by any suitable means and in the present instance I prefer to use a drive means whereby the screens (if more than one) may be driven in unison from a main drive shaft,

and whereby any or all of the screens or lamps, or both, may be adjusted without interrupting the continuity of drive.

A main drive shaft 25, driven in any suitable manner, is arranged substantially parallel to the tube 13, and the junction boxes 14 are provided with bearings 26 for rotatably receiving said shaft. A motor 27, or other suitable driving power, is arranged on a bracket 28 carried by the tube 13, said motor having a gear 29 carried by its armature and meshing with the gear 30 carried by the main drive shaft 25.

Adjacent each of the junction boxes 14 the shaft 25 carries a worm 31. A gear 32 is secured to each of the hubs 21 of the screens, and between each gear 32 and the worm 31 I have provided a flexible driving shaft 33 with gears 34 and 35 at its opposite ends, adapted to mesh with the gears 31 and 32 respectively. In this manner there is a flexibility of movement and there may be an adjustment of the brackets 7, 8, and of the lamp casings, without in any way interrupting the rotation of the color screens.

The devices may be used wherever found applicable, either for advertising or display purposes, or for theatres. The colors of the screens may be as desired.

What I claim as new and desire to secure by Letters Patent is:

1. In a device of the kind described and in combination, a lamp, a rotatable screen for said lamp, means for adjusting said screen about an axis extending laterally of its rotational axis, and drive means for rotating said screen at any point in its adjustment.

2. In a device of the kind described and in combination, a series of lamps, individual rotatable screens for said lamps, means for adjustably supporting said screens so that they may be moved to change their rotational axes a main drive shaft for all of said screens, and intermediate drive means connecting each screen with said main shaft for continuously rotating said screens.

3. In a device of the kind described and in combination, a lamp, a rotatable screen for said lamp, means for pivotally adjusting said screen, means for pivotally adjusting said lamp relative to said screen about an axis perpendicular to said first-mentioned pivotal axis, and drive means for continuously rotating said screen.

4. In a device of the kind described and in combination, a series of lamps, individual rotatable screens for each of said lamps, means for independently adjustably supporting each of said screens, a main drive shaft, gears at intervals on said drive shaft, gears at each of said screens and adjustably movable therewith, and individual flexible shafts between said first and second-mentioned gears to drive said screens.

5. In a device of the kind described and in combination, a series of lamps, individual rotatable screens for said lamps, means for individually adjusting said screens, a main drive shaft for all of said screens, gears at intervals on said drive shaft, gears at each of said screens, and intermediate flexible shafts having gears at their ends meshing with the gears at the main drive shaft and 10 at the screen for driving said screens.
6. In a device of the kind described and in combination, a supporting frame, a lamp carried thereby, a screen rotatable relative to said lamp and carried by said frame, adjustable means for supporting said screen and lamp, means independent of said first-mentioned adjusting means for adjusting said lamp relative to said screen, and drive means for rotating said screen.
- 20 7. In a device of the kind described and in combination, a J-shaped supporting frame made in a plurality of adjoining sections and pivotally adjustable about its longer leg as an axis, a lamp mounted between said parallel legs and carried by the shorter leg, a screen encircling said lamp and rotatably carried by the longer leg, whereby said screen and lamp may be ad- 25
- justed in unison about the longitudinal axis of said longer leg, and said lamp may be 30 adjusted about an axis perpendicular to said pivotal axis of the longer leg.
8. In a device of the kind described and in combination, a supporting frame, a lamp mounted thereon, a rotatable color screen 35 encircling said lamp and comprising a pair of angular, coaxial side members of angle-iron formation, brace bars connecting said side annular members at their peripheries, color sheets between said members across 40 said spaced peripheries, spokes on one of said side members, a hub connecting said spokes, a rod rotatably supporting said hub on said supporting frame, angle members superimposed on said side members, and 45 means for clamping said sheets at the side edges between said side members and superimposed angle members.
- In testimony whereof, I have hereunto signed my name in the presence of two sub- 50 scribing witnesses.

GEORGE E. STEPHENSON.
